BUSINESS PURSE

David Di Mezza, Gloversville, N. Y.

Application December 18, 1947, Serial No. 792,475

3 Claims. (Cl. 150—35)

1

This invention relates to purses and has more particular reference to purses of the type known as business purses.

One object of the present invention is to provide a business purse having a large pocket substantially coextensive in area with the purse designed to receive bills and/or paper money, and a plurality of smaller pockets superimposed on the larger pocket, each being designed to receive coins of a different value, and having closure means provided for each of the pockets.

Another object of the invention is to provide a purse as characterized above, wherein the entrances to a group of the smaller pockets are located one above the other in ascending relation to provide ready access to the pockets and to facilitate the insertion of the proper coins in the pocket designed to receive them.

Another object of the invention is to provide a business purse which is simple in construction, inexpensive to manufacture and one which is efficient in the use for which it is designed.

Other objects and advantages of the invention will become apparent from the following specification when considered with the accompanying drawings, wherein:

Fig. 1 is a perspective view showing one form of business purse constructed in accordance with the present invention, in an unfolded position;

Fig. 2 is a vertical sectional view taken on line 2—2 of Fig. 1;

Fig. 3 is a vertical sectional view taken on line 3—3 of Fig. 1; and

Fig. 4 is a perspective view of the purse shown in Fig. 1, but shown in a folded position.

Referring now to the drawings, there is shown a preferred form of business purse constructed in accordance with the present invention. In Fig. 1, the purse is shown in flat, unfolded position. In Fig. 4, the purse is shown in a preferred folded position.

As shown, the purse is rectangular in outline, when unfolded, and is fabricated to provide a large pocket 10, substantially equal in area to the area of the purse, for the reception of bills and/or paper money and a plurality of smaller pockets, superimposed on the large pocket, for the reception of coins. Each of the smaller pockets is designed for the reception of coins of different value, i. e., pennies, nickels, dimes, half dollars, etc., and, in the particular embodiment illustrated five such pockets 11, 12, 13, 14 and 15, are shown.

The large pocket is formed by a large rectangular outer wall member 16 and an inner wall member 17 substantially coextensive in size and shape to the outer wall member. The wall members 16 and 17 are secured together, as by stitching, along one longitudinal edge and along the side edges. The free longitudinal edges of

2

the wall members 16 and 17 form the entrance to the pocket.

A small pocket 11 is formed in one end of the purse by a small, flexible rectangular wall member 18 superimposed upon and extending transversely of the wall member 17. The wall member 18 is secured along its inner longitudinal edge and along its side edges to the wall member 17, as by stitching. The free longitudinal edge of the wall member 18 is substantially coextensive with the inturned hemmed side edge of the wall member 17 (see Fig. 2), and these two longitudinal edges form the entrance to the pocket 11.

The remaining pockets 12, 13, 14 and 15 are formed by substantially rectangular wall members 19, 20, 21 and 22 which are superimposed on and secured to the wall member 17; the pocket 12 being formed by wall members 17 and 19; the pocket 13 being formed by wall members 19 and 20; the pocket 14 being formed by wall members 20 and 21; and the pocket 15 being formed by wall members 21 and 22.

The longitudinal side edges and the left hand end edges, as viewed in Figs. 1 and 2, of the wall members 19, 20, 21 and 22, are secured together and to the corresponding edges of the wall member 17, as by stitching. The free right hand edge of the wall member 19 terminates short of the left hand edge of the wall member 18, as viewed in Figs. 1 and 2, to form the entrance to pocket 12, and the right hand edges of the wall members 20, 21 and 22 terminate short of the right hand edge of the wall member 18 upon which they are directly superimposed, as best seen in Fig. 2, to form the entrances to pockets 13, 14 and 15, respectively.

The entrance to the pocket 10 is closed, as by means of a slide fastener 23, one element of which is carried by a flexible strip 24 secured, as by stitching, to the free longitudinal edge of the wall member 16, the other element of the slide fastener being carried by a flexible strip 25 which is superimposed on the lower longitudinal edge of the purse (as viewed in Fig. 1) and secured to the superimposed strips 17, 18, 19, 20, 21 and 22, (see Fig. 3).

The entrance to the pocket 11 is closed, as by means of a slide fastener 26, one element of which is carried by a flexible strip 27, secured, as by stitching, to the free longitudinal edge of wall member 18, the other element of the slide fastener being carried by a flexible strip 28, secured as by stitching, to and inbetween the inturned right hand edges of the wall members 16 and 17 (see Fig. 2).

The entrance to the pocket 12 is closed, as by means of a slide fastener 29, one element of which is carried by a flexible strip 30 secured, as by stitching, to the left hand edge of the wall member 18, the other element of the slide fastener

being carried by a flexible strip 31 secured, as by stitching, to the right hand edge of wall member 19.

The entrance to pocket 13 is closed, as by means of a slide fastener 32, one element of which is carried by a flexible strip 33 secured, as by stitching, to the free edge of wall member 19 in superimposed relation to strip 31; the other element of the slide fastener being carried by a flexible strip 34 secured, as by stitching, to the free edge of the wall member 20.

The entrance to pocket 14 is closed, as by means of a slide fastener 35, one element of which is carried by a flexible strip 36 secured, as by stitching, to the free edge of wall member 20 in superimposed relation to strip 34; the other element of the slide fastener being carried by a flexible strip 37 secured, as by stitching, to the free edge of wall member 21.

The entrance to pocket 15 is closed, as by means of a slide fastener 38, one element of which is carried by a flexible strip 39 secured, as by stitching, to the free edge of wall member 21, in superimposed relation to strip 37; the other element of the slide fastener being carried by a flexible strip 40 secured, as by stitching, to the free edge of wall member 22.

Preferably, and in the particular embodiment of the purse illustrated, the wall forming members 16, 18 and 22 are made of leather, while the wall forming members 17, 19, 20, 21 and 22, and the slide fastener carrying strips are made of cloth.

A purse constructed in accordance with this invention is extremely simple in manufacture. In fabricating the purse, the wall forming members are cut to the desired size and shape. Then, the slide fastener strips are secured to the proper edge of the wall forming members 16, 17, 18, 19, 20, 21 and 22; next, the wall forming strip 18 is secured along its inner edge to the wall forming member 17; next, the superimposed wall members 19, 20, 21, and 22 are properly positioned on wall member 17; and then the longitudinal edges of the wall members 17, 19, 20, 21 and 22, and their outer end edges, as seen in Figs. 1 and 2, are stitched together; then the longitudinal edges of wall members 17 and 18 are stitched together; then the above completed sub-assembly is placed in superimposed relationship on wall members 16 and one of their longitudinal edges and their outer side edges stitched together to form the completed purse assembly; then the completed assembly is turned inside out so that the longitudinal and end edges will all be turned in, as shown in Figs. 2 and 3; then, as a final step, the flexible slide fastener strip 25 is stitched to the longitudinal edges of the superimposed wall members 17, 19, 20, 21 and 22 and the side edge of wall member 18, see Figs. 1 and 3, to form the completed purse. The leather wall forming members are positioned so that the grain side of the leather will be on the outside of the completed purse.

From the foregoing, it readily will be seen that there has been provided a business purse which is extremely simple to manufacture and which has a large pocket for the reception of bills and/or paper money, and a plurality of smaller pockets for the reception of coins of different values. The location of the group of small pockets with their entrances positioned in ascending relation facilitates the insertion of the proper coins in the particular pocket designed to receive them.

While the purse has been illustrated and described as particularly designed for a business purse, obviously, it may be made of various sizes and shapes and used for various other purposes, such as a pocketbook or as a purse to be carried in a lady's handbag.

Having thus described the invention, what is claimed is:

1. A business purse comprising two elongated substantially rectangular flexible wall forming members secured together along one longitudinal and both side edges to form a bill pocket adapted to contain paper money; a plurality of rectangular flexible wall forming members superimposed upon each other and upon one of said first named wall forming members and having their longitudinal edges and one side edge secured to the corresponding longitudinal and side edges of the first named wall forming member on which they are secured, each of said plurality of wall forming members cooperating with the wall forming member on which it is directly superimposed to form a coin pocket open at one end and having its free edge portion detachably connected to the corresponding edge portion of the wall forming member on which it is directly superimposed to provide closure means for the pocket formed therebetween, the pockets formed by said plurality of wall forming members being adapted to contain coins of different values.

2. A business purse, as set forth in claim 1, wherein each of said plurality of wall forming members is of less length than the wall forming member on which it is directly superimposed,

3. whereby the entrances to the pockets formed by said plurality of wall forming members are positioned adjacent to each other in echelon order to facilitate the insertion of the proper coin in the proper pocket, and wherein the free edge portion of each of said plurality of wall forming members is detachably connected to the corresponding edge portions of the wall forming member on which it is directly superimposed by cooperative slide fastener elements secured to the respective wall forming members.

4. A business purse, as set forth in claim 1, wherein an additional wall forming member is superimposed on the first named wall forming member on which said plurality of wall forming members are superimposed, said additional wall forming member extending transversely of the purse and being positioned adjacent to the opposite side edge from said plurality of wall forming members and having its longitudinal edge adjacent said plurality of wall forming members and its side edges secured to the wall forming member on which it is superimposed to form a coin pocket, and closure means for said last named pocket.
